UNITED STATES PATENT OFFICE.

FREDERICK W. YOST, OF NEW YORK, N. Y., AND BETHUNE G. KLUGH, OF CLEVELAND, OHIO, ASSIGNORS TO AMERICAN ORE RECLAMATION COMPANY, OF NEW YORK, N. Y., A CORPORATION OF NEW YORK.

IGNITION-FURNACE FOR SINTERING-MACHINES.

1,206,397.

Specification of Letters Patent.

Patented Nov. 28, 1916.

Application filed March 11, 1915. Serial No. 13,721.

To all whom it may concern:

Be it known that we, FREDERICK W. Yost and BETHUNE G. KLUGH, both citizens of the United States, and residents, respectively, of New York, in the county and State of New York, and Cleveland, in the county of Cuyahoga and State of Ohio, have invented a new and useful Ignition-Furnace for Sintering-Machines, of which the following is a full, clear, and exact description, reference being had to the accompanying drawings, forming part of this specification, in which—

Figure 1 is a transverse vertical section of one form of ignition furnace embodying our invention; Figs. 2 and 3 are similar views illustrating two different modifications; Fig. 4 is an end view of the ignition furnace shown in Fig. 2; Fig. 5 is a section, taken 15 on the line V—V, Fig. 2, and Fig. 6 is a transverse section through the combustion chamber of Fig. 3, the section being taken 20 on the line VI—VI.

Our invention has relation to an ignition 25 furnace for sintering machines, particularly of the continuous Dwight and Lloyd type.

In sintering metal bearing materials with various forms of the blast roasting or sintering process, the complete and thorough ignition 30 of all portions of the sintering charge is an essential element of the process. If one portion of the surface of the charge is fully ignited and another portion is incompletely ignited, the sintering action will proceed 35 more slowly, or will partially or wholly fail under that part of the surface that has been incompletely ignited. Poor ignition, therefore, results in a smaller output, due either 40 to a slow rate of sintering, or to the production of spoiled product.

Various fuels are available for use in igniting sintering charges, such as gasolene, kerosene, crude oil, fuel oil, tar, natural gas, coke oven gas, and illuminating gas. It is 45 sometimes desirable to have available more than one form of fuel for igniting purposes, so that a temporary failure of one kind of fuel supply will not result in a serious loss of output. For this reason it is 50 desirable to employ a type of ignition furnace which is interchangeable for use with two or more kinds of fluid fuel. Heretofore it has been necessary to use a specific type of ignition furnace for each kind of

fluid fuel used, and a change from one kind 55 of fuel to another has necessitated a resulting serious loss of time.

In the treatment of iron-bearing ores and blast furnace flue dust at blast furnaces and steel works, it is, of course, desirable to use 60 for ignition purposes the cheapest fluid fuel which is available. This is blast furnace gas. Such gas ordinarily has a heating value of from eighty to one hundred B. T. U.'s per cubic foot, compared with five hundred to 65 six hundred B. T. U.'s per cubic foot in illuminating gas, and nine hundred to one thousand B. T. U.'s in natural gas. Heretofore, however, it has not been practically 70 possible to burn such a lean gas as blast furnace gas in small jets, and for that reason the more expensive fluid fuels have been utilized instead in sintering operations.

At blast furnace plants, blast furnace gas is practically a waste product, and if it can 75 be used for sintering purposes, a saving of ninety per cent. or more of the cost of igniting a sintering charge can be effected.

Our invention is designed to provide an ignition furnace in which the fuel mixture is 80 so divided and burned as to obtain a practically unbroken line of flame of uniform intensity across the full width of the sintering charge.

A further object of the invention is to 85 provide apparatus of this character which is particularly adapted to the use of lean gases such as blast furnace gas, for the charge ignition; but which is capable, with slight change, of being quickly adapted for use 90 with any kind of fluid fuel.

A still further object is to render the apparatus adjustable for any depth of sintering charge or for any character of flame required.

Other objects of the invention will herein-after appear.

Referring first to that form of our invention illustrated in Fig. 1, the numeral 2 designates one of the pallets of a Dwight 100 and Lloyd continuous sintering machine, having the grate 3 upon which the sintering charge 4 is placed.

5 designates a gas and air mixer of well known type, and having the pipe connection 6 which leads to the blast furnace gas supply main or other source of lean gas supply. Said mixer has another connection 7

with an air supply pipe. Both the gas and air are preferably supplied under pressure. When using blast furnace gas, we prefer to supply both the air and the gas to the mixer 5 at pressures from two to three times as great as when natural gas, coke oven gas, or illuminating gas are employed. 8 is a valved pipe leading into another mixer 9 in the pipe connection 7, and which may be employed, when desired, to supply a richer gas for admixture with the lean gas. This may or may not be used. We prefer to employ it, however, since it not only provides means for enrichment of the blast furnace 15 gas when necessary, but also affords an independent source of supply of gas for the furnace in case of any failure of the blast furnace gas.

The mixer 5 has a pipe connection 10 with a distributing chamber, which is shown as consisting of an upper section 11 and a lower section 12. Fitted between these two sections is a diaphragm 13 which serves as a distributing plate and which is provided 25 with a plurality of holes or perforations 14. Fitted in the bottom of the lower section 12 are a plurality of burner orifices or nozzles 15 which are spaced in such relation to each other that the flame, as developed when it reaches the upper surface 30 of the sintering charge 4, forms a practically continuous line of flame from one side of the charge to the other. The holes in the distributing plate 13 are so proportioned 35 and located with reference to the burner nozzles 15 that the nozzles near each side of the charge secure a due proportion of the gas, to prevent a hot ignition flame at the center of the charge and a weak ignition 40 flame at the side portions thereof.

16 is a combustion chamber which is placed below the distributing chamber and its burner nozzles. This combustion chamber has a fire-brick lining 17 which practically fills the chamber, except that where the two sections of the lining are abutted 45 at the center of the chamber they are cut away to form a plurality of vertical openings or passages 18 which lead downwardly 50 into a combustion space 19 of inverted V-form. The principal function of this combustion chamber is to store up heat in its brick lining so as to maintain the combustion of the gas at a sufficiently high temperature. On this account, the combustion space 19 is made as small as possible and the side walls are brought near to each other so that the row of gas jets burn in close 55 proximity to the highly heated sides of the chamber.

The ignition furnace as a whole is supported by hangers 20 which are provided with suitable adjusting means, such as the turnbuckles 21. The distributing chamber 60 is supported above the combustion chamber

by the adjusting bolts and nuts 22. The adjustable hangers 20 permit of varying the distance between the upper surface of the sintering charge 4 and the lower surface of the combustion chamber. In the construction shown in Figs. 1 and 2 the pallet 2 is 70 shown as having relatively deep sides which project above the lower surface of the combustion chamber 16, this illustrating the use of the ignition furnace where the sintering 75 charge varies through a considerable range of depth and occupies ordinarily only a portion of the total depth of the pallet.

It is at all times desirable to space the combustion chamber as close to the upper 80 surface of the charge as conditions will permit, so as to reduce the volume of cold air drawn into the charge along with the ignition flame, in order to maintain the ignition at the highest temperature possible. 85 For materials that lie quiescently during the ignition period there need be provided only a mechanical clearance between the lower edge of the combustion chamber and the upper surface of the sintering charge. When 90 materials are sintered which contain an appreciable amount of combined water, particles of the sintering charge decrepitate and are thrown in contact with the heated 95 surface of the combustion chamber if the minimum clearance is employed.

By means of the adjustable connections 22 the quantity of secondary combustion air entering the combustion chamber between the distributing and combustion chambers 100 may be controlled as may be desired.

The two gas supply connections 6 and 8 provide means whereby in case the blast furnace gas is insufficient in quantity or is too lean in quality a shift can readily be 105 made to the other source of supply. Varying proportions of both gases can be used, both supply pipes being provided with valves so that the supply of either gas can be shut off or the desired proportion of each 110 used.

Figs. 2, 4, and 5 show substantially the same general construction as Fig. 1, and corresponding reference characters are applied to similar parts, with the letter ^a added. In Figs. 2 and 4 we have, however, omitted the mixing chamber 5 and the lean gas supply pipe 6, and have shown a single mixer 9^a having an air supply pipe connection 7^a and a gas supply pipe connection 8^a, the mixer 9^a being connected directly to the distributing chamber. This construction is particularly adapted for use with rich gases such as illuminating or coke oven gas. As shown in Figs. 2 and 5 the relation of the distributing chamber to the combustion chamber is 115 that which is adapted for use of a relatively rich gas, where a portion of the air required for complete combustion is supplied to the mixer 28, and the remainder of the combus- 120

tion air is supplied to the top of the combustion chamber through the injector action of the burner nozzles. In using blast furnace or producer gas the lower surface of the distributing chamber should be in tight contact with the upper surface of the combustion chamber and the joint made as nearly air-tight as possible to prevent air being drawn in at this point.

10 Fig. 3 shows a construction especially adapted for the use of oil or tar as the ignition fuel. Parts in this figure which correspond to similar parts in Fig. 1 are given the same reference numeral with the letter *b* added. We have in this figure shown a slightly different form of pallet in which the pallet sides 26 are of less depth than in the preceding figures and do not project above the lower surface of the combustion chamber. In this figure, 27 designates the fuel supply pipe having the atomizing nozzle 28 arranged above a retort 29 which is secured to the upper section of the distributing chamber. This retort has a fire-brick lining 30, and is designed to burn the fuel oil or tar which is sprayed therein with slightly less air than is needed for complete combustion. This retort is maintained at a bright red temperature, which fixes the atomized oil in its partly burned condition into a fairly stable gas.

It will be readily seen that not only any one of the several forms of fuel supply connections illustrated may be readily attached to the same distributor without any change in the latter, but that, in fact, any other suitable fuel supply arrangement may be connected thereto, as may be desired in any particular case to make a quick change from one kind of fuel to another.

Our invention is distinguished from the ignition furnaces used in the prior practice of sintering in the following respects: The apparatus is interchangeable for use with various kinds of gaseous fuels. It is adaptable with slight alterations for burning fuel oil or tar by generating fuel gas in an integral part of the apparatus. It burns lean gas in small jets placed at close intervals, so that a line of flame of uniform intensity can be extended across the full width of the sintering charge. Relatively high pressures are employed for both gas and air supply, and close regulation of both gas and air supply is possible so as to obtain very thorough mixing, and to permit the efficient burning of a lean gas such as blast furnace gas or producer gas. The combustion chamber is of restricted volume, with side walls near each other and maintained at a relatively high temperature so as to be able to continuously ignite lean gas mixtures and to burn such mixtures at a temperature above normal, and avoiding the usual great flame expansion with consequent drop in temper-

ature, thus producing high temperature ignition. By reason of the distributing plate interposed in the distributing chamber with its plurality of spaced and properly positioned holes, the supply of gas mixture is uniformly divided among the burner nozzles so as to obtain a practically unbroken line of flame of uniform intensity across the full width of the sintering charge. This distributing plate, together with the lower distributing chamber, also acts as a supplementary mixer for the gas and air, because of the throttling action of the small holes in said plate.

The ignition furnace as a whole is perfectly adjustable with respect to the upper surface of sintering charges of various depths, and the burner nozzles may also be adjusted with relation to the top of the combustion chamber so as to secure accurate control of the secondary air passing into the top of the combustion chamber.

The arrangement shown in Fig. 1 includes a mixer for lean gas, such as blast furnace gas, which is so connected with a mixer for fuel gas higher in heat units, that either gas may be used alone or a mixture of both gases may be used.

The apparatus as a whole is adaptable for use with any kind of fluid fuel, and is adjustable for any depth of sintering charge, or for any character of flame required.

Various changes may be made in the details of construction and arrangement of the several parts without departing from the spirit and scope of our invention as defined in the appended claims.

We claim:

1. An ignition furnace for sintering apparatus, having a combustion chamber and an interchangeable fluid fuel supply, substantially as described.

2. An ignition furnace for sintering apparatus, having a combustion chamber, supply connections leading to different sources of gas supply, and controlling means whereby either source of supply may be used independently of the other, or a proper mixture of both may be used, substantially as described.

3. An ignition furnace for sintering apparatus, having a combustion chamber and a detachable and interchangeable fluid fuel supply system, substantially as described.

4. An ignition furnace for sintering apparatus, having a combustion chamber, a distributing chamber formed with a transverse perforated distributing element, and a plurality of burner orifices below said element above the combustion chamber, substantially as described.

5. An ignition furnace for sintering apparatus, comprising a distributing chamber having a transversely arranged perforated distributing plate or diaphragm, a fuel sup-

- ply system connected thereto above the plate or diaphragm, and a series of burner orifices or nozzles below said plate or diaphragm, substantially as described.
5. 6. An ignition furnace or sintering apparatus, comprising a distributing chamber having a transversely arranged distributing plate, a fuel supply connection above said plate, and the lower portion of said chamber having a plurality of spaced burner nozzles, substantially as described.
7. An ignition furnace for sintering apparatus, comprising a distributing chamber having a fuel supply connection, a perforated distributing plate or diaphragm arranged transversely of said chamber, and a series of burner nozzles leading from the lower portion of said chamber, the holes in said plate and the burner nozzles being spaced and arranged to cause the supply of fuel mixture to be uniformly divided among the nozzles to obtain a practically unbroken line of flame of substantially uniform intensity across the full width of the sintering charge, substantially as described.
8. An ignition furnace for sintering apparatus, comprising a combustion chamber having diverging walls, a burner having a plurality of small jets arranged at close intervals, whereby a line of flame can be extended across the full length of the combustion chamber, there being an opening for each of said jets leading to the combustion chamber; substantially as described.
35. 9. An ignition furnace for sintering apparatus, comprising a combustion chamber having a refractory lining having an inverted V-shaped combustion space within its lower portion, and having a plurality of relatively small passages leading from its upper surface into said space, substantially as described.
10. An ignition furnace for sintering apparatus, comprising a fuel distributing chamber, a combustion chamber below the distributing chamber, and means for simultaneously adjusting said chambers vertically with respect to the sintering charge, substantially as described.
45. 11. An ignition furnace for sintering apparatus, comprising a distributing chamber, a combustion chamber below the distributing chamber, and means for vertically adjusting said chambers with respect to the sintering charge, together with means for also adjusting the relation between the distributing chamber and the combustion chamber, substantially as described.
50. 12. An ignition furnace for sintering apparatus, comprising a distributing chamber and a combustion chamber, said chambers being adjustable toward and away from each other, substantially as described.
60. 13. An ignition furnace for sintering apparatus, comprising a fuel distributing
- chamber having a plurality of burner nozzles spaced at close intervals, and a combustion chamber below said nozzles and having a restricted combustion space there being an opening for each nozzle leading to said space, substantially as described.
14. An ignition furnace for sintering apparatus, comprising a combustion chamber having a refractory lining or filling formed with a restricted combustion space whose lateral walls diverge downwardly, substantially as described.
15. An ignition furnace for sintering apparatus comprising a combustion chamber having a refractory lining or filling formed with a restricted combustion space whose lateral walls diverge downwardly, said space extending partly through the filling or lining from the bottom, and the lining having passages leading into the upper portion of said space, substantially as described.
16. An ignition furnace for sintering apparatus having an air and gas mixer connected to a source of lean gas supply, and another mixer connected to the first named mixer and also with a source of relatively rich gas supply, substantially as described.
17. An ignition furnace for sintering apparatus, having an air and gas mixer connected to a source of relatively rich gas supply, and another mixer connected to the first named mixer and also with a source of lean gas supply, together with control means whereby either or both sources of supply may be used, substantially as described.
18. An ignition furnace for sintering apparatus, comprising an air and gas mixer connected with a source of lean gas supply, and another air and gas mixer connected in series with the first air and gas mixer, and having a connection with another and different source of gas supply, substantially as described.
19. An ignition furnace for sintering apparatus, comprising a distributing chamber provided with a plurality of small jets arranged at close intervals, and a combustion chamber having a contracted combustion space and whereby it is maintained at a high temperature, there being an opening for each jet leading to the combustion chamber, substantially as described.
20. An ignition furnace for sintering apparatus, comprising a burner provided with a plurality of small jets arranged at close intervals, and a combustion chamber with a contracted combustion space whereby an ignition temperature for lean gas mixtures is maintained and in which a flame can be maintained over the entire combustion chamber above the sintering charge, substantially as described.
21. An ignition furnace for sintering apparatus, comprising a burner having a plurality of small jets arranged at close in-

- 5 tervals, a combustion chamber with a contracted combustion space and adapted to be maintained at a high temperature, and means for adjusting the burner and the combustion chamber in air tight relation to each other, whereby a line of flame generated from lean gas can be extended across the full width of the sintering charge, substantially as described.
- 10 22. An ignition furnace for sintering apparatus, comprising a burner having a plurality of small jets arranged at close intervals, a combustion chamber with a contracted combustion space and adapted to be maintained at a high temperature, and controlling means for closely regulating the

supply of secondary combustion air, whereby a line of flame generated from lean gas can be maintained across the full width of the sintering charge, substantially as de- 20 scribed.

In testimony whereof, we have hereunto set our hands.
